Primary Examiner — Darlington Ly(74) Attorney, Agent, or Firm — Dicke, Billig & Czaja,
PLLC(57) **CLAIM**

The ornamental design for a bicycle derailleur hanger extension, substantially as shown and described.

DESCRIPTION

FIG. 1 is a rear and right-side perspective view of the bicycle derailleur hanger extension showing our new design;
 FIG. 2 is a front and right-side perspective view thereof;
 FIG. 3 is a rear and left-side perspective view thereof;
 FIG. 4 is a front and left-side perspective view thereof;
 FIG. 5 is a right-side elevation view thereof;
 FIG. 6 is a left-side elevation view thereof;
 FIG. 7 is a front elevation view thereof;
 FIG. 8 is a rear elevation view thereof;
 FIG. 9 is a top plan view thereof; and,
 FIG. 10 is a bottom plan view thereof.
 The broken lines in the drawings illustrate portions of the bicycle derailleur hanger extension that form no part of the claimed design.

1 Claim, 5 Drawing Sheets(56)
